No. 690,568.

Patented Jan. 7, 1902.

E. H. ELDER.

JECTOR FOR BREAKDOWN GUNS.

(Application filed Dec. 31, 1900.)

(No Model.)

UNITED STATES PATENT OFFICE.

EDWARD H. ELDER, OF NORWICH, CONNECTICUT, ASSIGNOR TO THE
HOPKINS & ALLEN ARMS CO., OF NORWICH, CONNECTICUT.

EJECTOR FOR BREAKDOWN GUNS.

SPECIFICATION forming part of Letters Patent No. 690,568, dated January 7, 1902.

Application filed December 31, 1900. Serial No. 41,702. (No model.)

To all whom it may concern:

Be it known that I, EDWARD H. ELDER, a citizen of the United States, residing at Norwich, in the county of New London, State of Connecticut, have invented certain new and useful Improvements in Ejectors for Firearms, of which the following is a full, clear, and exact description.

This invention relates to that class of ejectors for firearms in which the act of "breaking down" the arm serves to set the shell-ejecting mechanism in operation to effect the starting of the shell from its seat in the barrel, either sufficiently to permit it to be grasped and withdrawn or with such force as to cause it to entirely leave the arm.

The particular object of this invention is to provide a device of the class mentioned which shall be of very simple construction and may be cheaply produced.

To assist in explaining my invention, I have provided the accompanying sheet of drawings, illustrating the same, as follows:

Figure 1 shows, partly in elevation and partly in vertical central section, a portion of an arm fitted up with my newly-invented shell-ejecting device. Fig. 2 is a view similar to Fig. 1, showing the said arm broken down and serving to explain the manner in which my newly-invented shell-ejecting mechanism operates. Fig. 3 is a rear end elevation of the barrel of the arm. Fig. 4 is a cross-sectional view of the said barrel, taken through the point at which it is hinged to the frame. Fig. 5 shows in elevation certain elements of the shell-ejecting mechanism detached from the arm and serves to illustrate a modification of my invention.

Referring to the drawings, the letter *a* denotes the frame of the arm, and *b* the barrel, the said frame and barrel being hinged together by the joint-pin *c*, which latter is fixed in the frame *a* and passes through the barrel-lug *d*, near the forward end of said lug, in substantially the usual manner.

The letter *e* denotes the ejector-bolt, said bolt being located in a chamber *b'*, beneath and parallel with the bore of the barrel *b*, and capable of limited longitudinal movement within the said chamber. The ejector-bolt *e* bears a head *e'*, which when the bolt is in its

inner or forward position forms a part of the rear end of the barrel and is formed with a recess *b*, in which the flange of the shell is received.

The letter *d* denotes a slot located in the lug *d* midway its width and extending parallel with the length of said lug from the forward end of the latter to a point substantially midway its length, and at or near its forward end the said slot opens into the ejector-rod chamber *b'*, already mentioned. The slot *d* is bridged near its forward end by the joint-pin *c* and also by a pin *f*, located in the lug *d* somewhat in advance of the hinge-pin. The pin *f* serves as the pivotal support of a lever *g*, located in the slot *d* and having its front or shorter arm extending into the chamber *b'* in such manner that a spring *h* may be confined between the said lever end and the adjacent end of the ejector-bolt *e*. The said lever *g* has a longer arm extending rearwardly at substantially right angles to the said shorter arm, the end of which said longer arm is turned upward and is adapted to enter the chamber *b'*, so as to engage a notch *e* in the ejector-bolt *e*. The ends of the lever *g* enter the chamber *b'* through the openings at the forward and rear ends of the slot *d*, serving to connect the said slot and chamber. Near the pivotal support *f* of the lever *g* the longer (rearwardly-extending) arm of the said lever passes through a notch *c* in the hinge-pin *c*, the bottom wall of which notch is adjacent the confronting edge of the said longer arm of the lever *g*.

When the arm is closed, as shown in Fig. 1, and the ejector-bolt *e* is in its forward position, the spring *h*, confined between the said bolt and the shorter arm of the lever *g*, serves to retain the said lever in such position that the end of its longer arm engages the notch *e* of the ejector-bolt. Upon breaking down the arm the act of rocking the barrel upon the joint-pin *c* moves the longer arm of the lever *g* upward until the edge of the said longer arm is carried into contact with the bottom wall of the joint-pin notch *c*. Continued rocking of the barrel upon the joint-pin *c* then results in causing the lever *g* to swing upon its pivotal supporting-pin *f* until the end of the longer arm is withdrawn from the ejector-bolt notch *e*.

The lever g leaves the ejector-bolt notch e^2 slightly in advance or simultaneously with the completion of the breaking down of the arm, and upon such releasing of the ejector-bolt e the spring h acts at once by expansion to shoot the said bolt rearward, and, assuming a shell k to have been in place in the barrel b , such action of the said bolt carries the shell from its seat in the barrel, the bolt-head e' engaging the flange of the shell in the usual manner and as before explained.

The rearward travel of the ejector-bolt e is limited by its engagement with the head-block a' of the frame a , and upon the closing 15 of the arm the bolt-head e' rides downward upon the face of the said head-block, causing the ejector-bolt e to move forward into its chamber b' and causing also the compression of the spring h between the bolt end and the 20 shorter arm of the lever g . The spring h when under compression rocks the lever g , so as to hold the end of the longer arm of the lever in engagement with the ejector-bolt e , and the said bolt in its forward travel rides 25 upon the said lever end until the latter is coincident with and enters the notch e^2 of the ejector-bolt, which action occurs upon the return of the bolt to its normal or starting position.

30 While the spring h is found in practice to operate satisfactorily in the manner described to accomplish the ends for which it is provided, in addition to the said spring means may also be provided (shown in Fig. 35 5) for positively starting the ejector-bolt from its seat upon the breaking down of the arm, thus overcoming any possible tendency the bolt might have to stick in its seat in the chamber b' .

40 Referring now to Fig. 5, the letter e^3 denotes a shouldered-down extension of the ejector-bolt e , the forward end of which extension is adjacent the shorter arm of the lever g , and upon said extension the spring h is mounted. 45 When the lever g is rocked upon its pivotal support f in the act of breaking down the arm, the shorter arm of the lever is rocked into engagement with the adjacent end of the shouldered-down bolt extension e^3 simultaneously with the withdrawal of the end of the 50 longer arm of the lever from the ejector-bolt notch e^2 , as shown in dotted lines in Fig. 5. Continued rocking of the lever then serves, through its engagement with the said ejector-bolt extension e^3 , to start the said bolt rearward positively, after which the spring h acts

in the manner already described to complete the rearward travel of the said bolt to discharge the shell.

Having now described my invention, I claim—

1. In a breakdown gun, in combination, a notched ejector-bolt mounted to slide in the barrel-lug, a bell-crank lever pivotally mounted in said lug and having one of its arms extending rearwardly with its end bent upwardly to engage in said notch of the ejector-bolt, a member fixed with relation to the lever and disposed rearward of the pivotal point of the latter in position to contact with said rearwardly-extending arm and force its engaging end out of the notch of the ejector-bolt when the barrel is swung open, and a spring arranged between the other arm of said lever and the adjacent end of the ejector-bolt, substantially as described.

2. In a breakdown gun, the combination with a notched ejector-bolt mounted to slide in the barrel-lug, and the joint-pin, of a lever intermediately pivoted in said lug forward of the joint-pin and having an arm extending rearwardly beneath the pin with its rear end bent upwardly to engage in said notch of the ejector-bolt, said arm of the lever adapted to contact with said pin when the barrel is swung open and effect the withdrawal of its engaging end from the notch of the ejector-bolt, and a spring arranged between the other arm of the lever and the adjacent end of the ejector-bolt, substantially as described.

3. In a breakdown gun, the combination with a notched ejector-bolt mounted to slide in the barrel-lug, and the joint-pin notched transversely in its under side, of a lever intermediately pivoted in said lug forward of the joint-pin, and having an arm extending rearwardly beneath and positioned in said notch and having its rear end bent upwardly to engage in said notch of the ejector-bolt, said arm of the lever adapted to be moved to withdraw its engaging end from the notch of the ejector-bolt by contact with the joint-pin when the barrel is swung open, and a spring arranged between the other arm of said lever and the adjacent end of the ejector-bolt, substantially as described.

Signed at Norwich, Connecticut, this 14th day of December, 1900.

EDWARD H. ELDER.
